UNITED STATES PATENT OFFICE.

MARY E. TRAVIS, OF EVERGREEN, ALABAMA.

FIREPLACE AND GRATE.

SPECIFICATION forming part of Letters Patent No. 741,192, dated October 13, 1903.

Application filed March 17, 1903. Serial No. 148,196. (No model.)

To all whom it may concern:

Be it known that I, MARY E. TRAVIS, a citizen of the United States, residing at Evergreen, in the county of Conecuh and State of Alabama, have invented certain new and useful Improvements in Fireplaces and Grates; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in combined open fireplaces and grates; and it consists in the provision of a device of this nature adapted to be seated in a fireplace-recess and so constructed that it may be readily adjusted for use either as a grate or fireplace-casing; and it consists, further, in the provision of sides and bottom of the casing, which are made of suitable plate-iron, the inner walls of which are provided with projections or ribs adapted to support a grate-bar having a flanged edge, which is notched and adapted to be held in place by cut-away or shouldered portions in the edges of the sides, while a removable and angled back is adapted to rest upon the tops of the sides and to be held by ribs, with a suitable space intervening between the same and the rear wall of the casing.

The invention consists, further, in various details of construction and combinations and arrangements of parts, which will be herein-after fully described and then specifically defined in the appended claims.

My invention is illustrated in the accompanying drawings, which, with the letters of reference marked thereon, form a part of this application, and in which—

Figure 1 is a perspective view of the device adjusted for use as a grate. Fig. 2 is a similar view showing the apparatus adjusted for use as an open fireplace. Fig. 3 is a detail view of the grate. Fig. 4 is a detail view of a perforated metallic partition.

Reference now being had to the details of the drawings by letter, A represents a casing the side walls of which are made of thick iron, either cast or plate, and B designates

the bottom, which has two arms B' projecting from the rear end thereof and passing through apertures in the rear wall of the casing. The front edge of said bottom has a flange B², the ends of which project beyond the edges of the sides of the casing, and upon the inner face of each side are ribs C, which are adapted to support a grate D, which is made substantially of the shape of the bottom, having three arms D' integral with the rear edge thereof and which are adapted to be inserted through the apertures E, formed in the rear wall of the casing, while the opposite longitudinal edges of the grate rest upon said ribs. On the forward edge of the grate D is a flange F, the ends of which project beyond the side of the casing, and the upper edge of said flange F is notched, as at F', at two locations, and the forward edges of the sides are recessed, forming shoulders G, which are adapted to be engaged by said notched portions, thus securely holding the sides from bulging or moving outward. Ribs H are formed vertically on the side walls of the casing, and a removable partition K, preferably perforated and bent at right angles, is provided, which has cut-away portions beneath the angled part of said partition, forming shoulders K'. The horizontally-disposed portion of said partition which projects over the tops of the sides is adapted to rest upon the same, while the rear edge of said horizontally-disposed portion rests upon the top of the back of the casing.

When the device is adjusted for use as a grate-burner, it appears as illustrated in Fig. 1 of the drawings; but when an open fireplace is wished the grate D and the perforated partition may be removed, thus adapting the device for use as an open fireplace having sides, back, and bottom of suitable thick metal taking the place of fire-brick.

A cross-piece N, having notches N' at opposite ends, is provided and connects the upper edges of the sides of the casing, said notches being adapted to engage notches M in the front edges of the sides, while the ends of the strip N project beyond the sides and afford means for supporting any masonry which may be positioned over the fireplace-casing.

While I have shown a particular construc-

tion of apparatus illustrating my fireplace-casing, it will be understood that I may make alterations in the detailed construction of the same without departing from the spirit of the 5 invention.

Having thus fully described my invention, what I claim as new, and desire to secure by Letters Patent, is—

1. An improvement in fireplaces comprising metallic sides and apertured back, said sides having ribs on their inner faces, a movable flanged grate having arms projecting from the rear end thereof adapted to engage the apertures in said back, the flange of said 15 grate projecting beyond said sides, and having recessed portions designed to engage under shoulders formed in the edges of the sides, and a partition forming a hot-air chamber, as set forth.
2. An improvement in fireplaces comprising sides with ribs on their inner faces and shouldered edges, a rear wall having apertures therein, a bottom with flanged edge, a flanged grate having arms projecting from the 25 rear edge thereof and adapted to engage said apertures in the rear wall of the casing, said flange of the grate projecting beyond the sides of the casing and having notches in its upper

edge engaging under said shouldered edges, a perforated angled metallic partition having 30 horizontally-disposed projections resting on the top of the sides of the casing, as set forth.

3. An improvement in fireplaces and grates comprising metallic sides, ribs on their inner faces, a bottom, an apertured rear wall forming, with said sides and bottom, a casing, a flanged grate adapted to rest upon said ribs and having rearwardly-projecting arms engaging apertures in said rear wall of the casing, the flange of said grate having notches 40 in its upper edge designed to engage under shoulders formed on the front edges of the sides of the casing, a strip having oppositely-disposed notches engaging the notches in the edges of said sides, and a removable angular 45 partition having a horizontally-disposed part wider than the vertical portion thereof and designed to rest upon the tops of the sides of said casing, as set forth.

In testimony whereof I hereunto affix my 50 signature in presence of two witnesses.

MARY E. TRAVIS.
